UNITED STATES PATENT OFFICE.

JUDSON ALBERT DE CEW, OF MONTREAL, QUEBEC, CANADA.

WOOD PRODUCT.

1,075,552.

Specification of Letters Patent.

Patented Oct. 14, 1913.

No Drawing.

Application filed January 22, 1912. Serial No. 672,760.

To all whom it may concern:

Be it known that I, JUDSON A. DE CEW, of the city of Montreal, in the Province of Quebec and Dominion of Canada, have 5 invented certain new and useful Improvements in Wood Products, of which the following is a full, clear, and exact description.

The object of this invention is to provide 10 a wood product which will be resistant to the attack of ferments, fungi and insects; and at the same time to provide a method whereby a soft wood may be rendered harder and more resistant to mechanical or 15 physical wear.

A further object is to provide a method of greatly reducing the cost of treatments by the well-known processes of wood preservation.

20 In the treatment of wood by impregnation with oil, it is necessary to use comparatively large quantities of oil to thoroughly impregnate the fibro-cellular bodies, and a large excess of oil must remain in 25 the wood without resultant benefits. By the use of this invention, the exact amount of oil necessary for preservation is introduced and this is carried into the wood in the form of an emulsion, until the desired 30 depth of penetration is obtained.

The present invention consists essentially in mixing suitable quantities of waste sulfite liquor and oil in the form of an emulsion, which is used to impregnate the fibro-cellular bodies. I may if desired introduce 35 any soluble salt which in itself will not emulsify with oil, but which when mixed with oil and waste sulfite liquor will form a perfect emulsion. It will thus be seen 40 that two preserving agents such as oil and a soluble salt may be combined in the form of an emulsion with a third preserving agent, and in this way the physical difficulties of impregnation by the usual 45 methods are overcome.

The period of treatment as well as the temperatures and pressures employed vary according to the results desired.

In carrying out my process, timber in 50 the form of boards, or the like, is placed in a closed tank and subjected to a steaming process, after which the steam and air are withdrawn from the tank by any suitable means such as a suction pump. By with-

drawing the air and steam from the material, the wood is left free to readily absorb the mixtures or emulsions mentioned. Seasoned wood may be treated without a steaming process. If the seasoned wood is being treated the material is simply immersed in the mixture or emulsion consisting of suitable quantities of waste sulfite liquor and crude oil or creosote oil, the steaming process being eliminated. To this emulsion may be added soluble salts such as chlorid of zinc, mercuric chlorid, sulfate of aluminium, sulfate of copper, or sulfate of iron. These salts are readily dissolved by the mixture, and form with the waste sulfite liquor and oil an emulsion which impregnates the fibro-cellular body without, however, leaving an excess of the materials within the cellular cavities. In this way, the relative amounts of the preserving materials may be limited to the desired 75 quantities, and may be controlled to meet various requirements. The absorption of the emulsion may be increased by subjecting the contents of the vessel in which the wood is placed to pressure. After the mass 80 has been allowed to cool the excess material is removed. For certain purposes the operation may be repeated if necessary. As a result of the impregnation and absorption of organic material, the wood is made 85 heavier, harder and stronger.

By introducing waste sulfite liquor, several important results are accomplished. The waste sulfite liquor alone acts as a preservative and hardening medium, and 90 being a cheaper material may replace in part any of the other preservatives used. The most important function, however, of the waste sulfite liquor is to act as an emulsifying agent. Its capacity for forming an 95 emulsion with oil makes it possible to combine definite proportions of oil with any water soluble salts. Another important function of the organic matter of the waste sulfite liquor, when used with any mixture 100 containing creosote or other oil, is that it greatly reduces the rate of evaporation of the lighter oils from the mixture.

Having thus described my invention, what I claim is:

1. A wood product consisting of a fibro-cellular body treated with a mixture of waste sulfite liquor and oil.

2. The herein described product consisting of a fibro-cellular body impregnated with a mixture of waste sulfite liquor, oil and a soluble salt.
- 5 3. The herein described product consisting of a fibro-cellular body impregnated with an emulsion of waste sulfite liquor, creosote oil, and a soluble salt.

In witness whereof I have hereunto set my hand in the presence of two witnesses. 10

JUDSON ALBERT DE CEW.

Witnesses:

STUART R. W. ALLEN,
G. M. MORELAND.
